OSAKA, JAPAN

COUNTING TABLE

Application filed August 28, 1930. Serial No. 478,491.

This invention relates to a counting table which consists of a series of bars arranged closely in parallel so as to make a surface, each bar being yieldably held in its position by a spring or springs so that it can be lowered independently from others when a pressure is applied to the bar.

When coins lay flat on a plain surface of a counting table it is difficult to pick them up. According to this invention the surface of a counting table consists of a number of yieldable members, so that the members on which a coin lays will be lowered by the pressure of fingers while it is being grasped or picked, and the coin can be easily picked up due to the deformation of the surface.

Referring to the attached drawings, Fig. 1 is a plan view of a counting table according to this invention, Fig. 2 is a sectional elevation of the same, and Fig. 3 is a transverse sectional view.

In the drawings, 1 is a bar of oblong section with convex surface. A number of such bars are arranged in parallel and closely in contact with each other so as to make a corrugated surface. Each bar is held in its position by means of a spring or springs 2, so that it can be lowered against the action of the springs, but its highest or normal position is limited by the front and rear edges of the base plate 4, where the jaws 3 on both ends of the bar are prevented from rising. One end of the spring is secured to the base plate 4, while another end thereof is secured to the bar. The base plate 4 has a side plate 4a on each longitudinal side which limits the width of the counting table.

The whole surface between the side plates may be composed of a series of the yieldable bars, but some part of same may be replaced by solid plates 4b, as shown in the drawings. This modification is useful for a large table. The bars 1 and the solid plates 4b have projected points *a* and *b* at front and rear ends, respectively, so that the length of the counting table is limited by the projected parts *a* and *b*.

The table is firmly fixed to or removably placed on a convenient stand which is disposed between counting men so as to place

the projected portions *a* and *b* in front of the men.

When coins are placed on the table, they can be easily grasped by a hand, because each bar yields in accordance with the pressure of each finger so that the surface of the table becomes an irregular one and the coins are no more flatly placed on the surface. In case a certain part of the surface is made solid, the coins scattered on the solid surface are first swept to the yieldable surface and then they should be grasped.

Claims:

1. A coin counter comprising a base member, springs extending upwardly therefrom and a plurality of closely arranged parallel bars normally forming a substantially plane surface resiliently mounted on said springs above the base member.

2. A coin counter comprising a base member, springs extending upwardly therefrom, a plurality of closely arranged parallel bars normally forming a substantially plane surface yieldingly mounted on said springs about the base member, and means for limiting the upward movement of the bars from the base member.

3. A coin counter comprising a base member having a peripheral flange extending outwardly from at least two edges thereof, springs extending upwardly from the said base member, a plurality of closely arranged parallel bars normally forming a substantially plane surface yieldingly mounted on said springs above the base member and having means thereon cooperating with the said flanges for limiting the upward movement of the bars from the base member.

In testimony whereof I affix my signature.

KEIJI TANAKA.
